[57] CLAIM

The ornamental design for combined mail and newspaper box with support, as shown and described.

DESCRIPTION

FIG. 1 is a left side elevational view of the combined mail and newspaper box with support showing my new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a front perspective view thereof with the doors in open condition;

FIG. 7 is a reduced back elevational view thereof; and,

FIG. 8 is a reduced front elevational view, with the door frame seals and magnetic latches removed for clarity of illustration.
